(57) **CLAIM**

The ornamental design for a portion of a watch, as shown and described.

DESCRIPTION

FIG. 1 is a front view of a portion of a watch showing my new design;

FIG. 2 is a perspective view thereof;

FIG. 3 is a side view thereof;

FIG. 4 is a side view thereof taken opposite FIG. 3;

FIG. 5 is a bottom view thereof; and,

FIG. 6 is a top view thereof.

The broken line showing of the top and bottom of the band and the side buttons is for illustrative purposes only and forms no part of the claimed design. The unshown back of the watch forms no part of the claimed design.
